HIGH VOLTAGE FUSE

Joseph Slepian, Pittsburgh, Pa., assignor to Westinghouse Electric & Manufacturing Company, a corporation of Pennsylvania

Application July 27, 1927, Serial No. 208,686

13 Claims. (Cl. 200—120)

My invention relates to electrical circuit interrupting devices and particularly to fuses for alternating current circuits.

One object of my invention is to provide a circuit interrupter that shall be applicable to high-voltage alternating current circuits.

Another object of my invention is to provide a structure for interrupting a circuit that shall confine an electrical arc and cause it to expand 10 predominantly in one direction.

Another object of my invention is to provide a fuse having insulating expansion recesses of such length that the arc, for the particular current at which the fuse is rated, shall not quite completely fill those recesses.

A further object of my invention is to provide a device of the above indicated character that shall have a sufficient length of arc dissipating recesses so that the current shall be interrupted 20 with a minimum arc voltage, that is to say one which will produce the minimum destructive effect upon the insulation.

Heretofore, it has been the practice in the art of designing fuses for high-voltage alternating currents, to utilize a liquid medium such as oil, pyrene, carbon tetrachloride and the like, for cooling the arc and for preventing its re-ignition after the alternating current has passed through zero value. Disadvantages are present 30 in the use of this type of fuse as the container must be hermetically sealed to prevent the liquid from leaking or evaporating. A further disadvantage inherent in a liquid fuse, is that due to cost and maintenance. A fuse of this 35 type must necessarily be returned to the manufacturer for renewal and an additional supply of fuses must be kept on hand to replace those being renewed. As the initial cost of installation is high, it follows that the maintenance cost 40 may prove burdensome.

The circuit interrupting structure of my invention, embodying a restricted medium of air to extinguish the arc, avoids the employment of a liquid medium, whereby the initial cost and 45 the maintenance thereafter is materially reduced. My invention provides a fuse that may be cheaply manufactured and that may be renewed in the field with very little effort, enabling it to be kept in substantially constant operation.

I have found that if the arc resulting from the opening of the circuit is confined between insulating members it may be interrupted and arc re-ignition prevented even more effectively than in structures employing a liquid medium, 50 or magnetic means. After the arc is thus di-

rected between insulating walls that confine the arc to expansion laterally, the conductivity of the arc path therein will be rapidly reduced as the current decreases and the arc will be permanently extinguished as soon as the current 60 passes through zero.

These and other objects of my invention will be made apparent by the following description and its illustration in the accompanying drawings, in which;

Fig. 1 is a view, partly in section and partly in elevation, of a fuse embodying my invention;

Fig. 2 is a cross-sectional view of Fig. 1, taken on the section line II—II;

Fig. 3 is a volt-ampere curve of an arc in air; 70

Fig. 4 is a volt-ampere curve of an arc that is wholly or partially confined by an insulating medium;

Fig. 5 is a view, partly in section and partly in elevation, of a circuit breaker embodying my 75 invention, and;

Fig. 6 is a view in cross-section of the confining member taken along the line VI—VI.

My invention comprises, in general, a circuit interrupting structure 1 that is provided with an 80 enveloping member having an insulating confining recess or recesses of a particular dimension and number, wherein an arc may be drawn and allowed to expand in a manner hereinafter more fully described.

Two particular forms of my invention are shown in the accompanying drawings. In sheet 1 a fuse structure is shown in which the fuse 1 has a main body portion 2 and a threaded ferrule 3 attached to each of its ends. Terminal caps 4 are screwed 90 on the ferrules 3 and are employed as terminals for electrically connecting the fuse 1 to an electric circuit. A fuse element 5 is attached to the interior of the top terminal 4 by clamping one of its ends against a washer 6. The other end of the 95 fuse 5 is connected to an electrical conducting element 7 that extends through slotted insulating members 8 and 9 and that is connected to the lower terminal 4 by means of a flexible shunt 11 attached thereto by means of a washer 12. The 100 slotted insulating members 8 and 9 are supported in the main body portion 2 by any method common to the art and is here shown supported by the cement 10. The lower end of the electric conducting element 7 cooperates with one end of 105 a coil spring 13 that has its other end attached to washer 12, the spring 13 being under tension when the fuse 1 is in operating condition.

Owing to the stresses that the fuse member 5 would be subjected to by the biasing spring 13, 110

a particular type of fuse member should be employed, one that will not be distorted by repeated heating due to small overloads. The type illustrated in the drawings which does not constitute any part of my present invention, is a preferred form consisting of a low melting solder uniting fusible material of a higher melting point. The fusible material has a reduced section for rupturing on short circuit currents while the low melting solder will release the fuse member when sufficient heat produced by an overload current is present. This construction prevents the heating of the fusible material by currents just less than suffice to melt it, from producing distortion under tension of the coil spring 13.

The insulating members 8 and 9 that are supported in the main body portion 2 by the cement 10, have deep parallel slots 15 of approximately the same width, disposed perpendicular to a central slot 16 between their adjacent faces.

It was found by experiment that as the distance between the insulating members 8 and 9, or as the width of the slots 15 and 16 was reduced, the circuit voltage which could be interrupted per inch length of the slots was materially increased. Further experiments disclosed that for arcs between copper terminals in insulating slots $\frac{1}{8}$ inch wide with a current of 550 amperes at 60 cycle, circuit voltages of 1400 volts per inch of arc would be successfully interrupted. It was with slots of approximately this width that successful experiments were carried out.

Assuming the fuse to be connected in a high voltage alternating current circuit, upon a short-circuit occurring therein, the fuse element 5 will be ruptured at its reduced section 14, the electrical conducting element 7 will be released. Due to the tension in the coil spring 13, the element 7 is drawn through the slot 16, drawing with it the arc formed in the top chamber of the fuse.

The arc so drawn will fill a greater or less portion of the slots 15 or 16, depending on the magnitude of the current at any instant, but the arc voltage will be a constant, namely that minimum voltage at which an arc can be maintained in a slot of the width of 15 or 16. If the current in the arc increases, the arc will merely spread and occupy a larger portion of the slots 15, 16 without an increase of arc voltage, provided the current is not so great that the slots 15, 16 do become completely filled with the arc.

As the arc current diminishes, the portion of the slots occupied by the arc also diminishes, but of course there is a lag in this because of the time taken for ions to recombine. However, this lag will be small, because of the rapid recombination of ions on the walls of the slots, and because of the close proximity of every part of the arc to slot wall.

After the arc current passes through zero, if the arc does not re-ignite, the voltage across the fuse will rise to the open circuit value in a very short time depending on the nature of the circuit. For ordinary commercial circuits, this time is between 1/50,000 and 1/250,000 seconds. During this time, the ions in the space are disappearing mostly by recombination. If the ions disappear sufficiently rapidly, the rapidly rising voltage will not be able to break the space down, and the arc will not re-ignite. But if the ions do not disappear quickly enough, the rapidly rising voltage will break down the space and cause the arc to re-ignite. By making the slots narrow, all parts of the arc are brought close to the walls and recombination of the ions is thereby hastened.

Hence, in narrow slots, a high circuit voltage per inch length of arc can be interrupted.

But while the width of the slot is determined by the circuit volts to be interrupted per inch length of arc, the lateral extent of the slots is determined by the condition that if the arc is confined in too small a space, the energy input into the arc becomes so great as to destroy the insulating walls. By permitting the arc to expand laterally not only is the energy input into the arc reduced, but the energy input per inch of slot wall is also greatly reduced, so that the insulation is able to withstand the period of arcing. This will be made clearer by considering the properties of free and combined arcs.

It is well known from past experiments that the voltage required to maintain an unrestricted arc in air decreases as the current increases and vice-versa. The curve representing this relation is shown in Fig. 3. If, however, the arc is entirely confined as in a straight circular hole, the curve takes a different form, as shown in Fig. 4, in which the voltage from the time of the confinement of the arc will have an ascending value as the current further increases. This is illustrated by curve CED of the figure in which an increase of the current to the position J corresponds to a decrease in voltage to F. The point E corresponds to a condition where the arc completely fills the hole in the insulating medium; and as it can expand no further with an increase of current, the voltage curve will ascend as shown by the portion of the curve ED.

Further experiments disclose that an arc, confined as regards expansion in one direction, between two insulating members, will expand laterally therebetween, the length of the lateral expansion being a function of the current and the distance between the adjoining insulating members. The arc voltage during such expansion remains constant in value as previously stated, since an increase of current merely tends to expand the arc further between the insulating members.

When the current has increased to a value J, as shown in Fig. 4, the arc being confined between the opposite walls of the insulating medium and the voltage will have decreased from C to E, a further increase in current will cause the arc to expand laterally, the arc voltage remaining constant as shown by dotted lines EF.

The constant arc voltage is a function of the distance between the adjacent insulating members, since an increase of current causes a decrease in voltage until such time as the arc makes contact with the adjacent walls. This corresponds to an arc voltage at the lowest point of the curve, as at E in Fig. 4. If the distance between the adjoining insulating members is decreased, the constant arc voltage aforesaid will be greater, as illustrated by the dotted line GSH of the curve CGSH. It therefore follows that a higher constant arc voltage will be obtained if the distance between the adjacent insulating members is reduced.

In the aforesaid example, the current had reached a value J at the time its lateral expansion was limited on one side by the walls of the slot 16, resulting in a constant arc voltage EF. If, however, the distance between the insulating confining members is reduced, the arc will be confined before the current reaches a value J, as at a position K, resulting in a constant arc voltage GH of higher value than the arc voltage

EF obtained when the current increased to a greater value J.

Experiments disclosed that a distance of $\frac{1}{4}$ " between the insulating confining members will result in a constant arc voltage of approximately 50 volts per inch length of arc. If, however, the distance between the insulating confining members is reduced to $\frac{1}{16}$ " the resulting constant arc voltage will have a value of about 75 volts per inch.

If the confining space is limited so that expansion of the arc is limited in all directions at some value of current, a further increase of current results in a corresponding increase of the arc voltage which thereupon increases rapidly with each increase of current. It is therefore necessary to provide a confining space of cross-sectional area suited for the particular currents it is intended to interrupt to prevent the arc voltage, and with it the arc energy, from increasing to so excessive an amount as would destroy the confining insulating member and result in the restriking of the arc. This is also shown in Fig. 4 by the curves QR and ST, which show the arc voltage rapidly increasing from the constant values EQ and GS to R and T, respectively, when the arc has expanded sufficiently to fill the entire section of the slot.

It therefore follows that the time for accomplishing the extinguishing of an arc in accordance with my invention will be a half-cycle or less, since the current reaches zero value twice during the period of one cycle.

The foregoing description applies to any arc confined between insulating walls and free to expand in one direction only. Sheet 2 of the drawings illustrates another embodiment of my invention in which a circuit interrupter 17 comprises the usual operating magnet and separable contacts but instead of the arc-chute heretofore employed in the art, the drawings show insulating members forming a narrow slot for extinguishing the arc. This structure will now be more fully described.

The contactor 17 is mounted on an insulating base member 18 and comprises an iron core 19, coil 20 and armature 21, the armature 21 being supported on a movable arm 22 by a pin 23. The movable arm 22 is hingedly supported at its lower end to the iron core 19 by a pin 24, its upper end being the means for supporting a moving contact member 25. A stationary contact member 26 is rigidly secured to the base member 18 by a member 27 which is of conducting material and which is in circuit with the apparatus to be controlled. The other portion of the circuit illustrated by a conducting lead 28 is shown connected to the moving contact member 25. Current flow in a circuit connected with the conducting leads 28 and 29 is controlled by the position of the contact members 25 and 26.

A supporting member 30 is the means of support for two confining members 31 composed of soapstone or other arc resisting insulating material. The confining members 31 as shown in Fig. 6, are mounted near each other to form a narrow groove 32 constituting a deionizing structure of a type heretofore mentioned. The lower portion of the groove 32 tapers to a greater width to form a chamber for the reception of the arc. The lateral expansion of the arc is limited by the side wall of the members 31, while the longitudinal expansion is limited by the conductor members 33 and 34 which are separated by a distance corresponding to the rating of the cir-

cuit breaker. A flexible current carrying shunt 35 is employed to electrically connect the moving contact member to the conducting member 34. The other conducting member 33 is permanently connected to the stationary contact member 26. When the contacts are open, a circuit is thus formed through the plates 33 and 34 and the arc resulting from the opening of the contacts. Auxiliary contact members 36 and 37 of any type may be provided and these may be open or closed in either positions of the contact member and may be employed to operate any auxiliary circuit.

Assuming the contactor 17 to be in the closed position with voltage applied to the potential coil 20 to hold the armature close to the iron core 19, the contact members 25 and 26 will be in contact, completing the circuit through the conducting leads 28 and 29. When the voltage is reduced or cut off from the coil 20, the armature 21 will be released and the movable arm 22 will turn in a counter clockwise direction, due to gravity, about the pin 24, carrying the movable contact member 25 away from the stationary contact 26. The arc drawn upon separation of the contact members will move upward passing from the contact members 25 and 26 onto the plates 33 and 34 into the narrow space between the member 32 and will then be extinguished as a result of the deionizing effect of the narrow slot 32 in a manner heretofore described.

I have therefore provided a structure that is capable of interrupting high voltage alternating current circuits without the use of a liquid medium or magnetic structure as heretofore has been the practice.

My invention de-ionizes the conducting path of the arc when the value of the current decreases in such manner that the voltage gradient required to restrike the arc between the arcing terminals will be greater than the line voltage at all times after the current has reached zero value and the arc, after being extinguished, will fail to restrike when the voltage is re-established.

The construction of my invention is simple, resulting in an interrupting device having a minimum cost. In the form of a high voltage fuse, my invention is further useful, in that it can be renewed in the field by the mere application of a new fuse element, while heretofore, it has been necessary to return the entire fuse to the manufacturer and have it again renewed and hermetically sealed before it could be again applied to a high voltage electric circuit. It is therefore apparent that my type of fuse is much more economical, both in the saving of time and money, than any fuse heretofore invented of the aforesaid type.

As the structure herein described and illustrated is only specific embodiments of my invention, I do not intend it to be limited to fuse or circuit breaker structures, for the invention is applicable to circuit interrupting devices of many other forms. I further do not wish to be restricted to the specific arrangement of parts herein set forth, as various modifications thereof may be effected without departing from the spirit and scope of my invention. I desire, therefore, that only such limitations shall be imposed as are indicated in the appended claims.

I claim as my invention:

1. The combination in a fuse structure having a casing and end terminals, of an insulating member disposed within the casing and provided with a plurality of narrow connected slots, a fuse

element adjacent one of the slots, and biasing means passing through the said slot attached to the fuse whereby upon the rupturing of the fuse element the arc incident thereto will be drawn 5 into the one slot from which it may expand into the other slots.

2. The combination in a fuse structure having a casing and end terminals, of an insulating member disposed within the casing and provided 10 with a plurality of slots approximately one-sixteenth of an inch in width, a fuse element and a biased conductor passing through one of the slots, whereby upon the rupturing of the fuse element the arc incident thereto will be drawn into one 15 of the slots from which it may expand into the other slots.

3. The combination in a fuse structure having a casing and end terminals, of an insulating member disposed within the casing and provided 20 with a plurality of slots of uniform width, a fuse element and a biased conductor passing through one of the slots, whereby upon the rupturing of the fuse element the arc incident thereto will be drawn into the one slot from which it may expand 25 into the other slots.

4. The combination in a fuse structure comprising a casing and end terminals, of a pair of semicircular members of insulating material having a plurality of deep narrow slots disposed in 30 the faces thereof and assembled to form a cylinder, the said faces abutting each other to form an additional slot, a spring biased conducting element passing through the said additional slot, and a fuse element disposed on the upper terminal 35 above the said cylinder and engaging an end of the spring biased conducting element, whereby upon the rupturing of the fuse element, the arc incident thereto will be drawn into the said additional slot by the spring biased conducting element and may expand into the narrow slots adjacent thereto.

5. The combination in a fuse structure comprising a casing and end terminals, of a pair of semicircular members of insulating material having a plurality of deep narrow slots disposed 45 lengthwise in the faces thereof assembled to form a cylinder, the said faces engaging each other to form an additional slot, a fuse element associated with the said additional slot and electrically connected to an end terminal.

6. An alternating current fuse structure having a plurality of inter-communicating narrow insulated slots, a fuse element disposed adjacent one of the slots and means for biasing the fuse element, whereby the arc incident to the rupturing of the fuse element will be drawn into the said slot where it may expand into the other said slots and be extinguished when the current passes through zero value.

60 7. In a fuse structure, insulating means defining a narrow slot having a lateral dimension several times its width, a fuse element adjacent

said slot and in parallel relation therewith, and means for causing the arc incident to the rupturing of said fuse element to play in said slot and expand therein between said insulating means.

8. In a fuse structure, insulating members 80 having a narrow slot therein, a fuse element arranged to cause an arc in said slot, said slot having a lateral dimension several times its width and being arranged to closely confine the arc throughout its length in one direction and to allow it 85 to expand laterally in the other direction.

9. In a fuse structure, insulating members having a narrow deep slot therein, a conducting member having a fusible portion, extending through said slot and parallel therewith for drawing an arc in said slot, the lateral dimension of said slot being several times its width so that the arc is restricted in one direction and allowed to expand laterally in the other direction. 90

10. A circuit interrupting structure having 95 slotted insulating means for confining the expansion of an arc throughout its length in one direction and permitting it to expand in the other, said slot being less than one-fourth of an inch in width and having a lateral dimension 100 several times its width and means movable in said slot for initially drawing the arc therein.

11. In a circuit interrupter, separable means for drawing an arc, and insulating means for extinguishing the arc having side walls defining 105 a slot having a lateral dimension several times its width and said width being so narrow as to restrict the width of the arc and cause it to expand laterally, and said slot between said side walls being positioned between said means for 110 drawing the arc when in separated position.

12. In a circuit interrupter, separable means for drawing an arc, and insulating means for extinguishing the arc having side walls defining a slot having a lateral dimension several times 115 its width and said width being so narrow as to restrict the width of the arc and cause it to expand laterally, said separable means for drawing the arc being movable between the side walls of said slot for initially drawing the arc there- 120 between.

13. In a circuit interrupter, separable means for drawing an arc, and insulating means for extinguishing the arc having side walls defining a slot having a lateral dimension several times 125 its width and said width being so narrow as to restrict the width of the arc and cause it to expand laterally, said separable means for drawing the arc being movable between the side walls of said slot for initially drawing the arc 130 therebetween and means outside of said slot biasing said separable means for drawing the arc to separated position and means causing the separation of said means for drawing the arc upon the occurrence of a predetermined current. 135

JOSEPH SLEPIAN.
